ATTORNEY

UNITED STATES PATENT OFFICE

WILLIAM J. POLK, OF MADISON, WISCONSIN

CIGARETTE SERVER

Application filed February 18, 1931. Serial No. 516,735.

The objects of this, my present invention, are the provision of a cigarette holder and server, of a construction whereby the server normally closes the container and is swingable outwardly therefrom to arrange a single cigarette in a position to be removed by the user, but which will hold the cigarette and return the same into the container if the same is not removed from the server; one wherein the construction is such that the last cigarette will not be delivered by the server, its removal necessitating the tilting of the device which affords a great convenience to smokers who wish to know when their supply is low so that the same can be replenished while at the same time the smoker is assured of having at least one more cigarette; one wherein the server is not controlled by a lever or like device but is cast in a single piece; one wherein loose tobacco falling from the cigarettes is retained in the device so that the same will not soil the desk or table upon which the improvement is arranged, further one wherein the hinged closure for the container is in the nature of a spring member which can be slipped under a depression cast in the cover or a socket in the name plate which makes it possible to provide each server with a fixed name or advertising plate of different characters and further wherein one that is characterized by simplicity in construction, cheapness to manufacture and thorough efficiency in practical use.

To the attainment of the foregoing the invention consists in the improvement herein-after described and definitely claimed.

In the drawings:

Figure 1 is a front elevation of a cigarette container and server in accordance with this invention.

Figure 2 is an approximately central transverse sectional view therethrough.

Figure 3 is a sectional view approximately on the line 3-3 of Figure 2.

Figure 4 is a detail sectional view approximately similar to Figure 2 but showing the server swung to open position and the arrangement of the last cigarette in the container.

Figure 5 is a front elevation thereof.

The container 1 has its body portion of a rectangular formation and of a size to receive therein any desired number of cigarettes. The container, from its juncture with its ornamental base 2, is widened, the rear wall 65 provided by the said widened portion being arched, as at 3, the front wall being cut-away but the side walls are also arched, as at 4. There is a suitable space between the arched edges of the side 4 and the front of the container 1, and the rear wall of the container, at the juncture of the arched and straight portions thereof, is formed with an angle flange 5.

The widened sides of the container, directly above the base 2, are provided with alining inwardly directed trunnions 6 that are designed to receive therebetween the notched portion 7 provided upon an outwardly extending lug or enlargement 8 on the lower wall 9 of the server. The server is formed with a front wall 10 that is arranged at an angle with respect to the bottom wall 9 and the walls 9 and 10 are integrally formed with an arched or rounded top 11 of the server. The top wall 11 projects a suitable distance beyond the rear wall, while the front wall 10 extends a suitable distance above the top wall 11 and the front 10, at the upper corners thereof, is formed with outwardly projecting portions 12 that afford finger grips. The arched top wall 11 of the server has its outer portion, or the portion thereof joined to the front wall 10, cut-away for a suitable distance to provide the server with what I will term spaced arms 13 and these arms are formed with rounded depressions 14 of a size to receive therein a single cigarette 15.

As far as the description has progressed it will be apparent that the rear of the server is of a greater weight than the front thereof so that the server will automatically swing on the trunnions 6 to closed position. The depressions or pockets 14 are at all times in a 90 position to receive one of the cigarettes 15 and when the server is swung to open position the cigarette will be retained in the said depressions or pockets and will not fall therefrom so that it is necessary for the smoker to 100

withdraw the cigarette from the pockets. Thus it will be noted that the server is not in the nature of an ejector. If the cigarette is not withdrawn and pressure is relieved from 5 the outer edge or from the grip portions 12 of the server the same will automatically return into the container. By reference to Figure 2 it will be seen that all of the cigarettes except the cigarette resting on 10 the angle ledge or flange 5 are in a position to be received in the pockets 14 of the server and it will be obvious that the server must be tilted before this cigarette can be arranged in the pockets 14. This is an important 15 feature of the invention as when the server is moved outwardly and no cigarettes are deposited in the pockets 14 the smoker will be aware that his cigarette supply is almost exhausted and that the container requires 20 replenishing. However, he is also aware of the fact that he has one more cigarette to enjoy before refilling the container.

The container has an open top which is normally covered by a top or closure 16. The 25 top 16 is formed with a depression in which is arranged a name plate 17, and the name plate may have formed on its inner face substantially U or V-shaped sockets 18 that pass through suitable openings in the top 16. 30 There is passed through openings in the back of the container 1 spring arms 19, the outer ends of the said arms being bent angularly and passed through openings in the top 16, the said springs being bent angularly from 35 the parts thereof that pass through the back of the container and merge into straight extensions 20 which are passed through the spaced pairs of sockets 18. The spring arms which provide the hinge elements between the 40 top and the container thus serve as a means for holding the name plate on the top.

Loose tobacco falling from the cigarettes will be directed into the bottom of the container or between the walls 9 and 10 of the 45 server. The server may be readily removed from the container by simply raising the bifurcated lugs 8 thereof off of the trunnions, the space at the front of the container being sufficient to permit of the withdrawal of the 50 server therethrough and it is thought the foregoing description, when read in connection with the accompanying drawings, will fully and clearly set forth the construction and advantages of my improvement so that further 55 detailed description will not be required.

Having described the invention, I claim:

A container and server for cigarettes, said container comprising a substantially rectangular box-like member having a base, an 60 arched rear portion extending from the base and connected with the back proper of the container, an inwardly extending inclined lug at the juncture of the arched and straight portions of the back, the front of the container 65 from the base thereof being cut-away

a suitable distance and the sides of the said cut-away front being arched, and affording a space between the lower wall of the front and said sides, the widened portion of the sides having an inwardly directed trunnions, a server comprising a base having a lug extension which is bifurcated to receive the trunnions therein, a front formed with the base, and an arched top connected with the front and base and extending beyond the base, 70 said front having its upper corners provided with lateral extensions, the arched top, from the front of the server being centrally cut-away a determined distance to provide end arms, each of which is formed with an alining depression that affords a pocket for a single cigarette.

In testimony whereof I affix my signature.

WILLIAM J. POLK.
